ALBERT D. GROVER, OF MALDEN, AND EARL E. BARBER, OF BOSTON, MASSACHUSETTS,
ASSIGNORS, BY MESNE ASSIGNMENTS, TO AUTOSALES CORPORATION, A CORPORA-
TION OF NEW YORK.

VENDING-MACHINE.

1,287,294.

Specification of Letters Patent.

Patented Dec. 10, 1918.

Original application filed December 15, 1911, Serial No. 666,006. Divided and this application filed July 27,
1912. Serial No. 711,796.

To all whom it may concern:

Be it known that we, ALBERT D. GROVER and EARL E. BARBER, citizens of the United States, and residing, respectively, at Malden, county of Middlesex, State of Massachusetts, and Boston, county of Suffolk, State of Massachusetts, have invented certain new and useful Improvements in Vending-Machines, of which the following is a specification.

Our invention relates to vending machines adapted to be operated upon the deposition of a coin for the delivery of a suitable commodity, and has for its general object the provision of a machine which may be adjusted at will to operate with or without the deposition of a coin. Referring more particularly to the embodiment shown in the drawings for the sake of illustrating the principle of our invention, we have provided an ejector mechanism which is normally held against operation by a locking member. When a coin is deposited, the locking member is forced into releasing or inoperative position, and the ejector mechanism is free to complete its stroke of operation. To render the ejector mechanism operable without the deposition of a coin, we have provided separate means for moving the locking member into releasing position, so that the machine will operate as a free dispenser. In the embodiment we have shown, this separate means is in the form of a key-controlled releasing bolt, but it is obvious that it may be modified in many ways to accomplish the same purpose.

The desirability of a vending machine which may be regulated at will by the mere turning of a key, or otherwise, to act either as a coin-controlled vending machine or as a free dispenser, may arise in various situations. For instance, a machine containing our invention will find ready application on the cars of a railway train which runs in its course through several States, in all of which the use of public drinking cups on trains is prohibited by legislation, and in some of which the railroad company is compelled by law to furnish patrons free of charge with individual drinking cups. When the train passes through those States in which the company is not obliged to furnish patrons

free with individual drinking cups, our machine may be so set as to operate only upon the deposition of a coin. However, as soon as the train enters a State in which the law requires the railroad company to provide the travelers with individual cups free of charge, the conductor or other official adjusts the machine to operate without the requirement of a coin. The advantages of our invention will thus be apparent.

This application is a division of our application, Serial No. 666,006, filed December 15, 1911.

Referring to the accompanying drawings, Figure 1 is a sectional bottom plan view of a machine embodying our invention, the section being taken substantially on line 1—1 of Fig. 2, the parts being shown in normal or unoperated position; and

Fig. 2 is a vertical section on line 2—2 of Fig. 1, the parts being shown in operated position.

In the particular form of machine shown in the drawings, the different parts which go to make up the ejector mechanism are carried by a main casting or support indicated as a whole by A. This casting or support comprises a body portion 1 which terminates at its front end in a rounded platform 2. The body portion 1 is provided with upwardly extending side flanges 3 and rear flange 4 between which the magazine 5 is rigidly secured by means of rivets, screws or pins 6; or any other suitable manner. The magazine 5 is preferably made of sheet metal and is of proper size to accommodate the vendable articles in a vertical stack. For the sake of illustration we have shown a vendible article B in Fig. 2 in the form of a flat cup or envelop in which the upper side extends beyond the under side to form a mouth or opening 7. The front wall 4 of the magazine is provided at the bottom with a delivery slot 8 through which the articles are ejected.

The operating mechanism for causing the ejection of the articles may be of any suitable form or type. In the machine illustrated in the drawings, the ejector 9 consists of a flat plate arranged to slide at the bottom of the magazine and having at its rear end an upstanding lug 10 adapted to engage the lowermost article in the stack and force

the same forwardly through the delivery opening 8. When the vendible articles are in the form indicated by B in Fig. 2, the lug 10 is arranged to engage the article 5 at the gaping mouth 7 to insure the delivery of the article. The ejector 9 is rigidly connected with the coin slide 11 by means of a block 12 which operates in the slot 13 formed in the casting A, the parts being connected 10 together by screws or rivets 14, or in any other suitable manner. The coin slide 11, which operates beneath the casting A, is provided with a coin opening 15 which is normally in alinement with the coin opening 16 formed in the shell 2 of the main casting or support A. The coin slide 11 is provided with a pair of downwardly extending lugs 17 between which is pivoted the front end of the connecting link 18 by means of the 15 pin 19. The rear end of the link 18 is pivotally connected with the upper end of the arm 20 by means of the pin 21. The lower end of the arm 20 is pivotally mounted on the pin or lug 22 carried by the lower 20 end of the depending bracket 23, which is secured to the under side of the casting A, as by screws 24. The ejector mechanism is operated by means of the plunger rod 25 which is at its rear end pivotally connected 25 with the arm 20 by means of the pin 26. The plunger rod 20 passes at its forward end through an opening in the frame C which is secured to the underside of the main casting in any suitable manner, as 30 by means of screws 27. Frame C is provided with a pair of rearwardly extending portions 28 and 29 between which the coin slide 11 is movably mounted. The frame C is sufficiently spaced from the main casting A, as indicated at 30, to provide free 35 and easy movement for the coin slide 11. A spring 31 secured at its rear end to the arm 20 and at its forward end to the frame C, normally holds the operating plunger 25 40 and the connected ejector in the position shown in Fig. 1. By having the point of connection 26 between the plunger 25 and the arm 20 substantially midway of the latter, the stroke of the ejector slide 11 is substantially twice that of the push rod. The 45 push rod need therefore be operated only a slight amount to effect the ejection of the articles.

The extension 28 of the frame C is provided with a downwardly projecting bearing lug 32 which supports one end of the shaft 33. The other end of the shaft is non-rotatably supported in the downwardly extending flange 34 provided on the extension 50 29 of the frame C. The shaft 33 is provided with a flattened portion 35 which works in a vertical slot (not shown) in the bearing flange 34. The object of this connection 55 between the shaft 33 and the bearing flange 34 is to hold the shaft against rotation and

at the same time permit that end of the shaft to move vertically for a purpose to be presently explained. On the shaft 33 is rotatably mounted a sleeve 36 which carries at its outer end a sprocket wheel 37 and at 70 its inner end a coin-testing arm 38. The free or outer end of the arm 38 is so shaped as to form points 39 and 40 which are adapted to engage the deposited coin and test the same. This coin-testing device does 75 not, in and of itself, form part of our present invention, it being the subject matter of Patent No. 625,123, granted May 16, 1899 to J. G. W. Romans and A. D. Grover, as their joint invention. As we have shown 80 the machine in the accompanying drawings equipped with this Romans & Grover coin-testing device, we will describe the same for the sake of giving a complete description of what the drawings show. The sprocket 85 wheel 37 is arranged to engage with the teeth 41 formed at one edge of the coin slide 11, as best shown in Fig. 1. Whenever, therefore, the coin slide is operated, the sleeve 36 is rotated together with the coin-testing arm 38. A locking dog 42 is at 43 pivoted to the flange 34 of the frame C. The rear end of the locking dog is provided with a hooked portion 44 which normally lies in the path of movement of the lug 45, 90 extending laterally from the coin slide 11, as shown in Fig. 1. A suitably-arranged spring holds the locking dog 42 in the path of the lug 45. As shown in Fig. 1, the lug 45 is normally at some distance in front 100 of hooked portion 44 of the locking dog, so that the coin slide is normally free to move inwardly until the lateral lug 45 engages the locking dog. Although the ejector 9 is always operated during the free movement 105 of the coin slide 11, as just described, this movement of the ejector is what may properly be termed an inoperative or ineffective movement, because the ejector is not moved back sufficiently to cause the upright lug 10 to engage the mouth of the lowermost article. The purpose of this normally free movement of the parts is to give the coin-testing device a chance to test the deposited coin. Although the operation of 110 this device is fully described in the Romans & Grover patent above mentioned, the same may here be briefly stated as follows: In the normal position of the different parts which constitute the operating mechanism, as 115 shown in the drawings, the coin slot 15 provided at the forward end of the coin slide 11, is in alinement with the entrance slot 16 in the rounded shelf 2 of the main casting A. The coin-testing arm 38 normally 120 occupies substantially the position shown in the full lines of Fig. 1 and in dotted lines of Fig. 2. The deposited coin, substantially filling the slot 15, rests on the forward extension 46 of the frame C. As the rod 25 125 130

is then pushed inwardly, the coin is carried on by the slide 11. At the same time the testing arm 38 is rocked upwardly and the movement of the parts is so timed that the 5 point 39 bears against the inner shoulder of the raised edge of the coin. This temporary pivotal connection between the coin and the arm 38 forces the shaft 33 downwardly. As the downwardly moving end 10 of the shaft 33 extends over the locking dog 42, the downward movement of the shaft rocks the locking dog downwardly and removes the hooked end 44 out of the path of the lateral lug 45 on the coin slide 15 11. As the rod 29 is pushed in farther, the point 40 of the coin-testing arm 38 bears against the under surface of the coin after the point 39 has passed out of engagement therewith. This holds the locking dog 42 20 in depressed or releasing position until the lateral shoulder 47 on the coin slide 11 has passed the free end of the locking dog. Should the deposited check be a washer, the point 40 of the coin-testing arm would enter 25 the opening of the washer after the point 39 had passed out of engagement with the edge of the washer, whereby the locking dog 42 would rise into locking position to engage with the shoulder 47. This would 30 lock the coin slide against further movement.

It will, of course, be understood that we have here shown and described the coin-testing device of the Romans & Grover 35 patent merely for the sake of illustration, and that so far as the principle of our invention is concerned, any suitable coin-testing device and any suitable ejecting mechanism may be employed, provided the device 40 which normally locks the ejector mechanism against operation is capable of being moved into releasing position through the medium of the deposited coin.

We will now describe a preferred form 45 of means for moving the locking dog 42 into releasing position otherwise than through the medium of a deposited coin, so that the machine may operate without the deposition of a coin. A bell crank 48 is pivoted 50 at 49 to the extension 50 on the flange 34 of the frame C. The upwardly-extending rear arm of the bell crank is provided with a lateral lug 51 which extends over the locking dog 42 near the free end thereof, 55 as best shown in Fig. 2. The free end of the forwardly extending arm of the bell crank 48 is arranged over the bolt 52 of a suitable lock L secured to the inside of the coin box 53. This coin box also acts as a 60 housing for inclosing the parts projecting beneath the casting and is removably supported therefrom by means of lugs 54 and 55. The lugs 54 are carried by the downwardly extending flange 56 at the rear of 65 the casting and enter corresponding open-

ings in the coin box 53. The lugs 55 are carried on the front wall of the coin box 53 and enter corresponding openings in the frame C. When the bolt 52 of the lock L is in withdrawn position, the bell crank 48 70 does not in the least interfere with the operation of the machine upon the deposition of a coin, as previously described in detail. The lateral lug 51 of the bell crank simply rests by gravity on the locking dog 42. 75 When it is desired to operate the machine without the deposition of a coin, the bolt 52 is thrown upwardly by means of a key inserted in the lock L. This upward movement of the bolt 52 throws the forward end 80 of the bell crank 48 upwardly and the rear end downwardly. As the lateral lug 51 lies over the locking dog 42, this rocking of the bell crank by the bolt 52 throws the free end of the locking dog downwardly out of 85 the path of movement of the lateral lug 45 and shoulder 49 on the coin slide 11. This operated position of the bell crank and locking dog is shown in Fig. 2. The locking dog 42 being thus rocked into inoperative 90 position, the ejector 9 is free to operate to the limit of its inward movement to eject the articles from the magazine, in exactly the same way as when the machine is operated upon the deposition of a coin. To 95 adjust the machine for operation with a coin only, it is but necessary to turn the key in the lock L to withdraw the bolt 52. If our machine is used on a train, the key to the lock L would be in the custody of the 100 conductor or other official. It will be understood that the means for adjusting the mechanism of the machine to permit its operation without, or only upon, the deposition of a coin, need not be key-controlled, 105 although the use of a key makes the adjustment an extremely simple matter. While we have herein shown and described a specific form of machine embodying the principle of our invention, we would have 110 it understood that we do not intend to be limited to any of the details of such specific form, as it is obvious that the idea of our invention may be mechanically carried out in a number of ways.

Having thus described our invention, what we claim as new and desire to secure by Letters Patent of the United States, is:

1. In a vending machine provided with a magazine for containing the vendible articles, the combination of an ejector adapted to eject such articles from the magazine, a hand-operated member connected with said ejector for actuating the same from the outside of the machine, a 120 coin-controlled pawl for normally holding said ejector locked against movement, and an independent arm adapted to be actuated by a key to move said pawl into releasing position, said arm being retained in its 125 130

actuated position, so that said ejector is free to be operated without the deposition of a coin.

2. In a vending machine provided with a magazine for containing the vendible articles, the combination of an ejector adapted to eject said articles from the magazine, mechanism for operating said ejector through the medium of a coin, an independent arm adapted to adjust said mechanism into position to cause operation of said ejector without the medium of a coin, and

an adjustable element associated with said arm for actuating the same, said element being operable from the outside of the machine by a key and adapted to remain in operated position. 15

In witness whereof, we hereunto subscribe our names, this 5th day of July, 1912.

ALBERT D. GROVER.
EARL E. BARBER.
